UNITED STATES PATENT OFFICE.

WALTER DE FREAR, OF ALBANY, NEW YORK.

GARMENT-HANGER.

No. 886,042.

Specification of Letters Patent.

Patented April 28, 1908.

Application filed March 12, 1908. Serial No. 420,573.

To all whom it may concern:

Be it known that I, WALTER DE FREAR, of Albany, in the county of Albany and State of New York, have invented certain new and useful Improvements in Garment-Hangers; and I hereby declare that the following is a full, clear, and exact description thereof, reference being had to the accompanying drawings, which form part of this specification.

10 This invention is an improvement in garment hangers, especially designed for coats, trousers and skirt hangers, and can be used for hanging entire suits of clothes, as it embodies both a coat supporter, and a skirt and 15 trousers supporter.

The object of the invention is to provide a hanger which will keep the garments in shapely condition, and which will accommodate the collar of a coat hung thereon at the 20 point of suspension, without causing unsightly creases therein; and will support the shoulders of such coat so as to maintain the shapeliness of the garment; and on which trousers or skirts can be hung either by the 25 foot-bands or waist-bands.

The invention consists in the peculiar novel construction of the hanger as hereinafter described and claimed, and illustrated in the drawings, in which—

30 Figure 1 is a front view of the complete hanger. Fig. 2 is a side view thereof; and Fig. 3 is an enlarged detail sectional view showing the connection of the hook to the yoke. Fig. 4 is an enlarged detail sectional view showing the connection of the suspending rod to the yoke.

As shown, the hanger comprises a yoke 1, preferably made of wood, over which a coat can be hung in the usual manner. This yoke 40 is provided with a suspending hook rod of peculiar form, see Fig. 2, preferably made of wire, and having its lower part or shank 2 transfixing the yoke at center thereof, and preferably attached thereto by having its 45 lower end bent upwardly and its extremity embedded in the underside of the yoke, as shown at 2^a. Just above the yoke the hook-rod has an arc-shaped collar receiving return-bend 2^b, the lower member of which is 50 about in the same plane as the top of the yoke, said arc-shaped bend lying at right angles to the plane of the yoke, and in the best position to receive the collar of a coat hung upon the yoke; the arc-shaped bend being 55 especially formed and designed for this purpose. From the extremity of the upper

member of the return bend, rises the hook proper, indicated at 2^c, which is formed preferably in a plane at right angles to that of the return-bend 2^b, and in substantially the 60 vertical plane of the yoke 1.

Under the yoke 1 is a suspending rod lying in the same vertical plane as the yoke, and having its major portion 3 straight and preferably slightly longer than the yoke. At the 65 ends of this major portion 3 the ends of the rod are bent upwardly and slightly inwardly, toward the adjacent overhanging ends of the yoke, as at 3^a; then the ends of the rods are bent inwardly, as at 3^b, almost parallel 70 with part 3, and then again bent sharply upward and outward, as at 3^c, the extremities of parts 3^c engaging inclined sockets or holes 1^c in the underside and near the ends of yoke 1, as shown. In this way the suspending rod 75 is firmly attached to the yoke, and owing to the inclination of the parts 3^c is practically rigidly connected with the yoke; and an important feature of the structure is that the parts 3^a form supports or shapers for the 80 shoulders of a coat hung upon the yoke and prevent collapse of the shoulders.

On the straight portion 3 of the suspending rod, are slidable spring-clamps 4, which can be adjusted to, and from each other, and by 85 which trousers or skirts can be suspended from the rod, as desired. If desired the clamps 4 can be slid out to the ends of the part 3, and a folded garment hung upon and over the part 3.

90 A number of garments can be hung upon this improved hanger, and each will be kept in neat and proper condition.

Having described my invention what I claim as new and desire to secure by Letters 95 Patent is:

1. A garment hanger comprising a yoke, a suspending hook connected therewith, and a suspending rod longer than the yoke and below the yoke, having its end bent upwardly 100 to form shoulder-supports for the garment, and the extremities of the upturned portions being connected to the yoke, substantially as described.

2. A garment hanger comprising a yoke, a 105 suspending hook connected centrally therewith and having a return bend above the yoke, and a hook above the bend; and a suspending rod below the yoke, having its ends bent upwardly to form shoulder-supports for 110 the garment, and the extremities of the upturned portions being outwardly inclined and

engaged with sockets in the yoke, substantially as described.

3. The herein described garment hanger comprising a yoke, a suspending-rod underlying the yoke, and having a straight portion projecting beyond the ends of the yoke, and upwardly and inwardly inclined portions at the ends of the straight portion forming supports for the shoulders of the garment, and also having outwardly inclined portions, at the upper ends of the shoulder supporting portions, said outwardly inclined portions engaging sockets in the underside of the yoke. 10
4. The herein described garment hanger comprising a yoke; a suspending rod, underlying the yoke and having a straight portion projecting beyond the ends of the yoke, and 15

upwardly and inwardly inclined portions at the ends of the straight portion, and inwardly extending portions at the upper ends of the shoulder supporting portions, and outwardly inclined portions at the extremities of the inwardly extending portions, said outwardly inclined portions engaging sockets in the underside of the yoke; and suspending 20 hook attached to the yoke, substantially as described. 25

In testimony that I claim the foregoing as my own, I affix my signature in presence of two witnesses.

WALTER DE FREAR.
